UNITED STATES PATENT OFFICE.

JOHN ACTON, OF LONDON, ENGLAND.

PAPER-FOLDING APPARATUS.

Application filed December 29, 1927, Serial No. 243,333, and in Great Britain December 15, 1926.

This invention relates to paper folding apparatus intended to fold lengthy strips of paper into a number of longitudinal folds; for example, paper printed with a number of repeated forms, one series on each fold, so that after the paper has been folded the folded strip could be passed through a typewriting or other machine and copies could be taken simultaneously on each fold. The complete sheet may be perforated or cut or both in any suitable manner along the folds and also, if desired, across the folds, for convenience in separating after use as a folded sheet. The folding device may however be employed for any purpose in which the paper sheet is to be folded into a number of relatively narrow strips, and the essential parts of the device can be made as an attachment to printing (by any standard process) or other paper operating machines. It can be adapted for example, to the production from the web of stationery, pamphlets, magazines, newspapers or books, illustrated or otherwise.

According to this invention the paper, after passing over or through feeding rollers or like devices, and, preferably, over an initial set of fold initiating devices (such as grooving rollers bearing alternately on the front and back of the sheet), is passed through a folding device consisting of a series of plates or formers which are arranged side by side fan-wise and are disposed so that their edges are on opposite sides of the paper, the fan-wise arrangement being such that the formers approach each other towards their delivery ends. The formers comprise thin, preferably tapered, plates arranged in staggered sets so that the plates of one set overlap with those of the other set to a progressively increasing extent, whereby the folds are gradually completed as the paper is drawn through the folding device, the paper as folded having its planes of folding transverse to the original plane of the paper. The grooving rollers and the formers are adjustable according to the character or width of the folds required, the formers being preferably connected at one end to adjusting members whereby the ends may be moved forwardly or rearwardly as required, while the other ends of the formers are connected to pivotally-mounted arms, which, if desired, may be adjustable transversely of the machine.

If desired the paper may be controlled along its free edges by rolling guide wheels

set at an angle and rotated either mechanically or by the sheet as it passes, ensuring the proper formation of the side folds. This device is of known type. The longitudinally folded paper is drawn between rollers as it emerges from the formers and cross folded into convenient lengths according to requirements.

In order that the said invention may be clearly understood and readily carried into effect, the same will now be described more fully with reference to the accompanying drawings, in which.—

Figure 1 is a side elevation, and

Figure 2 a front elevation, of a paper strip folding apparatus embodying this invention.

Figures 3 and 4 are sections on lines 3—3 and 4—4, respectively, of Figure 2.

A is the main frame of the apparatus, the chief part of the framework being vertical with an extension *a* at the side carrying the part of the apparatus through which the paper is fed prior to folding. B is the paper strip taken usually from a printing machine working in synchronism with the folding apparatus and after passing through preliminary operations drawn between the rollers C, C¹ at the top of the frame A, from which it descends vertically through the folding apparatus and in its folded condition forms the pile B¹ (Figure 2) at the bottom of the apparatus. For clearness the paper strip is not shown in Figure 2 except after it emerges from the folder. The feeding of the paper strip may be controlled from the drive of a printing cylinder D which drives the bowl *d* through the intermediate cylinder *d*¹ (Figure 1). Chain drives *d*² and *d*³ lead from the chain wheel *d*⁴ driven from the printing cylinder and effect the driving of the rollers which operate the paper feeding and folding mechanism as hereinafter described. The paper when it first enters the folding apparatus passes under a register roller E having adjusting means of ordinary type to keep the paper taut, the paper then passing over a second roller *e* and between rollers *e*¹ and *e*², the upper one of which forms a lineal perforator or slitter for cases in which it is desired to perforate at the folds. This arrangement is of any standard construction. The chain drive *d*² leads to a driving wheel *d*⁵ from which is driven the lower drawing roller C at the top of the machine through a chain wheel *c* on the roller *e* driven from the

wheel d^5 of the drive d^2 . The chain c^1 passes from the wheel c to the drawing roller C .

After passing through the lineal perforator the paper passes through a cross perforator F of standard type, this cross perforator being also driven by gearing from the printing cylinder D so that it registers exactly with any printing which has been impressed upon the paper strip before it passes into the folding apparatus. The cross perforator may be of any convenient character, forming perforations or slits. The paper passes over the roller f above which is the perforator f^1 operated by a rotating cam f^2 which allows the perforator to descend and effect its operation at the desired intervals, in a well known manner.

The paper enters the main part of the apparatus after passing between the drawing rollers C , C^1 adjustable on the top bar of the frame A then entering between front and rear adjustable grooving rollers G , mounted on adjustable arms g^1 on shafts g carried by brackets g^2 , so that the grooving rollers press alternately on opposite sides of the paper. The paper is thus formed with grooves so as to initiate the folds completed at the next stage.

The folding device proper comprises a series of plates or formers H , arranged in two sets so that the formers of one set are staggered with respect to those of the other set, said formers being secured at their upper ends to arms h^1 which are adjustably secured by set screws to a pair of shafts h and being carried by the two shafts alternately as shown in Fig. 1. The formers preferably consist of thin tapered plates which are spaced along the shafts and regularly increase their extent of overlap as viewed from the side from the top to the bottom of the group of formers so that as the strip B enters between the two sets of formers on passing from the rollers G , the folds are only slightly outlined, the overlap of the formers being small. The formers H as they descend both increase the overlap and approach each other as shown in Figs. 2, 3 and 4 until at their lower end h^2 they are separated only by a clearance for the paper and the paper strip passes out from the folder almost completely folded. It will be noted that the paper strip as it enters the folder has its plane transverse to the machine as viewed from the front, while by the time it passes from the folder the individual folds are in planes longitudinal of the machine. The formers are adjustable at their lower end according to the width of the folds required so as to cause more or less overlap of the formers as the paper descends. As shown in Figure 1 the formers at their lower ends completely overlap, but the amount of overlap and consequent width of fold can be varied by displacing the adjustable arms J , of which there are four, two being secured

to a shaft j , at the front, and the other two being secured to a similar shaft j , at the back of the formers. The upper ends of each pair of arms, J , are connected to a shaft j^6 , to which there are adjustably secured by set screws links j^1 , which are attached by slot and pin connections to thin plates j^2 , secured upon the lower ends of the formers H , the arrangement being such that one set of formers is supported from one of the shafts j , while the other set is supported from the other shaft. The arms J , are adjustable simultaneously from one of the shafts j , provided with an adjusting handle j^3 , through the medium of arms, j^4 , which are geared together at their ends through the toothed segments j^5 , which are secured to the shafts j . Alternate groups of formers can, by this means, be moved in opposite directions, so as to increase or decrease the amount of their overlap. The overlap may be variable if desired, to provide for different widths of folds. If one fold is to be produced outside of the formers guide wheels may act upon the paper near the edge to form the outer fold in a known manner.

The folded paper is drawn through the folder by rollers K a short distance below the lower edge of the formers at the apex of the fan formation as indicated in Figure 2. The rollers are geared together and driven in synchronism with the cross perforator F and the drive from the printing machine by a chain k to the chain wheel k' driven through the bevel gearing k^2 from a shaft L having chain wheel l over which the chain d^3 already referred to passes. The closely folded strip then passes between further rollers k^3 and through a transverse folding device M of known type from which it forms the pile B^1 consisting of the paper strip folded longitudinally and then folded transversely in folds of widths corresponding to the various printed sections which can be separated by tearing at the transverse perforations already formed. The final portions of the apparatus comprising the rollers K , transverse folder and other members are mounted upon the inner frame A^1 .

What I claim and desire to secure by Letters Patent of the United States is:—

1. Apparatus for folding a web of paper into a number of longitudinal folds comprising paper feeding mechanism, paper grooving mechanism consisting of grooving rollers acting on both sides of the paper to initiate the folds and a plurality of formers arranged side by side fanwise with their edges bearing alternately on opposite sides of the paper, the fanwise arrangement being such that the formers overlap each other to an increasing extent in the direction of their delivery end.

2. Apparatus for folding a web of paper into a number of longitudinal folds comprising

ing a plurality of formers arranged side by side fanwise so that they overlap each other to an increasing extent in the direction of their delivery end with their edges bearing alternately on opposite sides of the paper, the fanwise spreading of the formers being adjustable according to the widths of the folds required.

3. Apparatus for folding a web of paper into a number of longitudinal folds comprising a plurality of fanwise disposed formers having their edges bearing alternately on opposite sides of the paper, the said formers being arranged so that they overlap to a progressively increasing extent from their entering to their delivery end, and means adapted to permit the extent of overlap to be varied

in accordance with the width of fold required.

4. Apparatus for folding a web of paper comprising mechanism for transversely perforating the paper, a folding device for longitudinally folding the paper, the said folding device consisting of a plurality of formers so arranged as to overlap to a progressively increasing extent and extending longitudinally of the web and spreading out in the manner of a fan from the end at which the paper emerges to the end at which the paper enters, and a transverse folding mechanism for transversely folding the longitudinally folded paper along the transverse perforations.

JOHN ACTON.
